Primary Examiner — John R Yeh

(57) **CLAIM**

The ornamental design for a cleaning glove, as shown and described.

DESCRIPTION

FIG. 1 is a front, left side, top perspective view of a cleaning glove showing my new design;

FIG. 2 is a rear, right side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled region 9 shown in FIG. 1; and,

FIG. 10 is an enlarged view of the encircled region 10 shown in FIG. 2.

The broken lines depict portions of the cleaning glove that form no part of the claimed design.

1 Claim, 10 Drawing Sheets
